UNITED STATES PATENT OFFICE

CHARLES P. SCHLEGEL, OF ROCHESTER, NEW YORK, ASSIGNOR TO THE SCHLEGEL MANUFACTURING CO., OF ROCHESTER, NEW YORK, A CORPORATION OF NEW YORK

DESIGN FOR A GRIP STRAP

Application filed March 1, 1929. Serial No. 30,266. Term of patent 7 years.

To all whom it may concern:

Be it known that I, CHARLES P. SCHLEGEL, a citizen of the United States, residing at Rochester, in the county of Monroe and State of New York, have invented a new, original, and ornamental Design for a Grip Strap, of which the following is a specification, reference being had to the accompanying drawing forming part thereof.

In the drawings:

Fig. 1 is a view in elevation of the grip strap showing the attaching bracket in dotted lines; and

Fig. 2 is a bottom plan view of the same.

I claim:

The ornamental design for a grip strap, as shown.

CHARLES P. SCHLEGEL.
